US00D957486S

(12) **United States Design Patent** (10) **Patent No.:** **US D957,486 S**
(45) **Date of Patent:** **** Jul. 12, 2022**

(54) **CUTTER**(71) Applicant: **Vermeer Manufacturing Company**,
Pella, IA (US)(72) Inventors: **Stephen Daining**, Pella, IA (US);
Matthew Ryan Disselkoen, Pella, IA (US);
Claudio Carrafiello Verzilli,
Pella, IA (US); **Joshua Dean Nossaman**, Pella, IA (US)(73) Assignee: **Vermeer Manufacturing Company**,
Pella, IA (US)(**) Term: **15 Years**(21) Appl. No.: **29/815,729**(22) Filed: **Nov. 16, 2021****Related U.S. Application Data**

(62) Division of application No. 29/679,556, filed on Feb. 7, 2019, now Pat. No. Des. 939,599.

Primary Examiner — Nathaniel D. Buckner*(74) Attorney, Agent, or Firm* — Michael Best & Friedrich LLP(57) **CLAIM**

We claim the ornamental design for a cutter, as shown and described.

DESCRIPTION

FIG. 1 is a rear perspective view of a cutter according to the present disclosure.

FIG. 2 is a right side view of the cutter of FIG. 1.

FIG. 3 is a left side view of the cutter of FIG. 1.

FIG. 4 is a front view of the cutter of FIG. 1.

FIG. 5 is a rear view of the cutter of FIG. 1.

FIG. 6 is a top view of the cutter of FIG. 1; and,

FIG. 7 is a bottom view of the cutter of FIG. 1.

The portions of the cutter shown in broken lines form no part of the claimed design.
